UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

BAG-FRAME FASTENER.

Application filed April 21, 1922. Serial No. 555,922.

To all whom it may concern:

Be it known that I, HUGO TUECKMANTEL, a citizen of the United States, residing at Irvington, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bag-frame fastener; and the present invention has reference, more particularly, to a novel and simply constructed safety latch or lock for use with the hinged frame-sections of any of the well-known bag-frames employed with various kinds of travelling bags, suit-cases, and the like.

The present invention, therefore, has for its principal objects to provide a simply made and cheaply constructed bag-frame fastener in which the usual chambered shell of box is dispensed with, and in which in lieu thereof, a main plate provided with means for its attachment to the upper and outer face of one of the frame-sections is employed, said plate being provided with upward projecting marginal flanges, between which is pivotally disposed or hinged a manipulating plate or lever, from which extends in a downward direction from said latter plate or lever, and through an opening in the main plate, a frame-section engaging lock-post of the general character hereinafter more fully set forth.

Other objects of the present invention not at this time more particularly enumerated, will be clearly understood from the following detailed description of the present invention.

With the various objects of the present invention in view, the said invention consists, primarily, in the novel bag-frame fastener hereinafter set forth; and, the said invention consists, furthermore, in the novel arrangements and combinations of the various devices and parts, as well as in the

details of the construction of the same, all of which will be more fully set forth in the following specification, and then finally embodied in the clauses of the claims, which are appended to and which form an essential part of the said specification.

The invention is fully illustrated in the accompanying drawings, in which:

Figure 1 is a front elevation of a fragmentary portion of a bag-frame, provided with a bag-frame fastener showing one embodiment of the principles of the present invention, with the parts of the fastener illustrated in their closed and frame-engaging relations.

Figure 2 is a side elevation of the bag-frame fastener detached from the frame-section, showing the pivoted bolt-carrying plate and its bolt or lock-post, in their raised positions; and Figures 3 and 4 elevations of the respective ends of the bag-frame fastener, the various parts being represented in their closed relations.

Figure 5 is an end view of the fastener, looking in the direction of the arrow *x* in said Figure 2; Figure 6 is a horizontal sectional representation, said section being taken on line 6—6 in said Figure 2; and Figure 7 is a longitudinal vertical section of the said fastener.

Figure 8 is a similar vertical representation of a slightly modified construction of bag-frame fastener.

Similar characters of reference are employed in the said above described views, to indicate corresponding parts.

Referring now to the said figures of the drawings, the reference-character 1 indicates the main member of the outer frame-section of a bag-frame, upon the upper and outer face of which is adapted to be secured, in the desired positions, a pair of bag-frame fasteners of the general character and construction shown in the several figures of the drawings herewith accompanying, and described in the following specification; and the reference-character 2 indicates the other or inner frame-section of the bag-frame, said frame-sections 1 and 2 being suitably connected in any usual hinge-like manner, but not here shown.

Each bag-frame fastener consists, essentially, of a suitably formed main base-plate 3 provided at its respective marginal ends with downwardly projecting fastening lugs 5 or ears 4 for securing said plate upon the outer and upper face of the frame-section 1, substantially as shown in Figure 1 of the drawings.

Of course it will be evident that other 10 means may be employed for securing the said base-plate 3 in its position upon the said frame-section 1.

Projecting in upward directions from both of the longitudinally extending marginal 15 edges of the said base-plate 3 are longitudinally extending marginal flanges, as 5, which flanges, if desired, may be shorter in length than the length of the base-plate, as shown in the accompanying drawings. This arrangement of the said members is, however, 20 not essential.

Between the said flanges 5, the said base-plate 3 is made with a suitably shaped opening 6, the purpose of which will be presently 25 described.

At or near the one end of each flange 5 is a pin 7 which extends laterally across the open space between said flanges, and has its ends suitably secured to the respective 30 flanges, as shown and as will be clearly understood from an inspection of the several figures of the drawings. Pivotedly mounted upon said pin 7, by means of pivot members 8 in a hinge-like manner is a manipulating plate or lever 9 provided with a downwardly projecting lock-post or bolt 10 which extends through and is movably disposed in the previously mentioned opening 6 in the main base-plate 3, and is provided at its 35 free end with a suitably shaped stop-lug or projection, as 11. The said manipulating plate or lever 9 is of such width and length corresponding to the space between the two flanges 5, so that when in its closed position, shown in Figures 1, 3 and 4, its upper and outer face will be flush with upper edges of the said flanges 5, the parts thereby presenting in appearance, a shell or box-like structure usual in the general bag-frame fasteners now in ordinary use. The said manipulating plate or lever 9 is also usually of 40 such length, that its free end-portion 12 will extend beyond the ends of the said flanges 5, as indicated in Figure 1, said end-portion 12 thereby providing a suitable fingerpiece for the manipulation of said bolt-carrying plate or lever, as will be evident. At its pivoted or hinged end-portion, the said plate or lever 9 is made with a downwardly projecting 45 spring-engaging lug or finger, as 13, in active engagement with the part 15 of a suitably formed bifurcated spring-member 14, suitably secured in a manner as clearly illustrated in Figure 6 of the drawings, upon the

said base-plate 3, by means of rivets 15', or other fastening means. The arrangement of the said lug or finger 13 in slidable engagement with the part 15 of the spring-member 14 is such, that the said manipulating plate or lever 9, and its locking or retaining bolt or post 10, when raised, will be positively held in such raised position, and when lowered will close with a perceptible snap, as will be clearly evident.

In lieu of providing a separate spring-member 14, as hereinabove described, the main base-plate 3 of the fastener, as shown in Figure 8 of the drawings, may be formed with a spring-member or tongue 16; which is struck up out of said plate, and is integrally connected therewith, as at 17, the previously mentioned lug or finger 13 being in slidable engagement with the free end-portion 18 of said spring-member or tongue 16, as indicated in said Figure 8. In this construction, the said spring-member or tongue 16 is also provided with an elongated opening or slot 19 into and through which the lock-post or bolt 10 of the plate or lever 9 extends and is movably disposed therein.

It will be fully understood that bag-frame fasteners made according to the principles of the present invention may be secured to and employed with the hinged bag-frame sections of any of the usual bag-frames now in use.

Of course I am aware, that some changes may be made in the general arrangements and combinations of the several devices and parts, as well as in the details of the construction of the said parts, without departing from the scope of the present invention as set forth in the foregoing specification, and as defined in the clauses of the claims which are appended to the said specification. Hence, I do not limit my present invention to the exact arrangements and combinations of the various devices and parts as described in the said specification, nor do I confine myself to the exact details of the construction of the said parts, as illustrated in the accompanying drawings.

I claim:—

1. A bag-frame fastener comprising a base-plate adapted to be secured to a frame-section of a bag-frame, said base-plate being provided with a longitudinally extending opening, marginal flanges extending upwardly from and longitudinally with said base-plate so as to provide an open-ended member, a manipulating lever providing a cover-plate pivotally disposed between said flanges, and locking means connected with said lever and movable in the opening of the base-plate for engagement with a frame-section.

2. A bag-frame fastener comprising a base-plate adapted to be secured to a frame-

section of a bag-frame, said base-plate being provided with a longitudinally extending opening, marginal flanges extending upwardly from and longitudinally with said

5 base-plate so as to provide an open-ended member, a manipulating lever providing a cover-plate pivotally disposed between said flanges, and a frame-section engaging lock-post connected with and extending downwardly from said lever into and through the opening of the base-plate.

3. A bag-frame fastener comprising a base-plate adapted to be secured to a frame-section of a bag-frame, said base-plate being 15 provided with a longitudinally extending opening, marginal flanges extending upwardly from and longitudinally with said base-plate so as to provide an open-ended member, a pivot-pin secured between said 20 flanges, a manipulating lever providing a cover-plate disposed between said flanges and pivotally connected with said pin, a spring-plate secured to said base-plate, said spring-plate having an open portion corresponding to the opening in said base-plate, a spring-engaging lug in slidable engagement with a portion of said spring-plate, and locking means connected with said lever and movable in the openings of the said 25 30 spring-plate and base-plate for engagement with a frame-section.

4. A bag-frame fastener comprising a base-plate adapted to be secured to a frame-section of a bag-frame, said base-plate being 25 provided with a longitudinally extending opening, marginal flanges extending upwardly from and longitudinally with said base-plate so as to provide an open-ended member, a pivot-pin secured between said 40 flanges, a manipulating lever disposed between said flanges and pivotally connected with said pin, a spring-plate secured to said base-plate, said spring-plate having an open portion corresponding to the opening in said base-plate, a spring-engaging lug in slidable engagement with a portion of said 45 spring-plate, and a frame-section engaging lock-post connected with and extending downwardly from said lever into and through the openings of the said spring-plate and the said base-plate.

5. A bag-frame fastener comprising a base-plate adapted to be secured to a frame-section of a bag-frame, said base-plate being 53 provided with a longitudinally extending opening, marginal flanges extending upwardly from and longitudinally with said base-plate so as to provide an open-ended member, said flanges being shorter in length 60 than the length of the base-plate, a manipulating lever pivotally disposed between said flanges, said lever being of greater length than the length of said flanges to provide an extending portion adapted to be used as a

finger-piece, and locking means connected 65 with said lever and movable in the opening of the base-plate for engagement with a frame-section.

6. A bag-frame fastener comprising a base-plate adapted to be secured to a frame 70 section of a bag frame, said base-plate being provided with a longitudinally extending opening, marginal flanges extending upwardly from and longitudinally with said base-plate so as to provide an open-ended member, said flanges being shorter in length 75 than the length of the base-plate, a manipulating lever providing a cover-plate pivotally disposed between said flanges, said lever being of greater length than the length of said flanges to provide an extending portion adapted to be used as a finger-piece, and a frame-section engaging lock-post connected with and extending downwardly from said 80 lever into and through the opening of the 85 base-plate.

7. A bag-frame fastener comprising a base-plate adapted to be secured to a frame-section of a bag-frame, said base-plate being provided with a longitudinally extending 90 opening, marginal flanges extending upwardly from and longitudinally with said base-plate so as to provide an open-ended member, said flanges being shorter in length 95 than the length of the base-plate, a pivot-pin secured between said flanges a manipulating lever providing a cover-plate disposed between said flanges and pivotally connected with said pin, said lever being of greater 100 length than the length of said flanges to provide an extending portion adapted to be used as a finger-piece, a spring-plate secured to said base-plate, said spring-plate having an open portion corresponding to the opening in said base-plate, a spring-engaging lug in slidable engagement with a portion of said 105 spring-plate, and locking means connected with said lever and movable in the openings of the said spring plate and base-plate for engagement with a frame-section. 110

8. A bag-frame fastener comprising a base-plate adapted to be secured to a frame-section of a bag-frame, said base-plate being provided with a longitudinally extending opening, marginal flanges extending upwardly from and longitudinally with said base-plate so as to provide an open-ended member, said flanges being shorter in length 115 than the length of the base-plate, a pivot-pin secured between said flanges a manipulating lever providing a cover-plate disposed between said flanges and pivotally connected with said pin, said lever being of greater length than the length of said flanges to provide an extending portion adapted to be used as a fingerpiece, a spring-plate secured to said base-plate, said spring-plate having 120 an open portion corresponding to the open- 125

ing in said base-plate, a spring-engaging lug in slidable engagement with a portion of said spring-plate, and a frame-section engaging lock-post connected with and extending downwardly from said lever into and through the openings of the said spring-plate and the said base-plate.

In testimony that I claim the invention set forth above I have hereunto set my hand this 20th day of April, 1922.

HUGO TUECKMANTEL.
